US00D863557S

(12) **United States Design Patent** (10) Patent No.: **US D863,557 S**
(45) Date of Patent: **** Oct. 15, 2019**

(54) **LENS FOR DIGITAL DIAGNOSTIC DEVICE**

(71) Applicant: **Medimaging Integrated Solution, Inc.**,
Hsinchu (TW)

(72) Inventors: **Chu-Ming Cheng**, Hsinchu (TW);
Long-Sheng Liao, Hsinchu (TW);
Kuo-Lang Huang, Hsinchu (TW);
Kuan-Pao Lu, Hsinchu (TW)

(73) Assignee: **MEDIMAGING INTEGRATED
SOLUTION, INC.**, Hsinchu (TW)

(**) Term: **15 Years**

(21) Appl. No.: **29/597,908**

(22) Filed: **Mar. 21, 2017**

(51) LOC (12) Cl. **24-02**

(52) U.S. Cl.

USPC **D24/172**

(58) **Field of Classification Search**

USPC D24/172, 128, 186, 158, 137, 160;

D16/136; D15/140; D14/227; D10/46

CPC G02B 6/4292; A61B 3/0075; A61B 3/032;

H04N 5/2256; H04N 9/3114

See application file for complete search history.

(57) **CLAIM**

The ornamental design for a lens for digital diagnostic device, as shown and described.

DESCRIPTION

FIG. 1 is a perspective view of a lens for digital diagnostic device showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective front view thereof; and shown in an alternate position;

FIG. 9 is a perspective front view thereof, shown in an environment;

FIG. 10 is a perspective front view thereof, shown in an environment; and,

FIG. 11 is another perspective view of the lens for digital diagnostic device from the rear side.

In the drawings, the broken lines are for the purpose of illustrating environment only and form no part of the claimed design.

1 Claim, 11 Drawing Sheets
